Henry R. Dimsled

UNITED STATES PATENT OFFICE.

KINGSLEY R. OLMSTED, OF CHICAGO, ILLINOIS, ASSIGNOR TO GILES F. FILLEY, OF ST. LOUIS, MISSOURI.

SAWING-MACHINE.

Specification of Letters Patent No. 27,024, dated January 31, 1860.

To all whom it may concern:

Be it known that I, KINGSLEY R. OLMSTED, of the city of Chicago, in the county of Cook and State of Illinois, have invented 5 certain new and useful Improvements in Sawing-Machines; and I do hereby declare that the following is a full, clear, and exact description of the same, reference being had to the annexed drawings, making part of 10 this specification, and to the letters of reference marked thereon, in which—

Figure 1 is a general perspective view of a sawing machine, with my improvements attached. Fig. 2 is a detached view of the 15 improved inclined plane, the dotted lines showing the rising of the plane as the end of the set lever passes, and Fig. 3 is a vertical sectional view of the eccentric bearing or journal box of the change friction gear wheel, for changing from feed motion of 20 carriage to gig motion, the same letters having reference to like parts in each of the figures.

The nature of my improvement consists 25 in so constructing the inclined plane of the self setting apparatus (as heretofore patented by me on 10th November, 1857), that when the set lever on the set rod passes backward with the gigging motion of the carriage, the lower end of said plane rises and allows the fixed arm with roller at the end of the set lever to pass freely under it, after 30 which the end of said plane drops to its proper position for operating the set lever, so as to give the desired set to the log, as the feed motion of the carriage again commences. This mode of constructing and 35 operating the inclined plane, allows the knuckle joint and its spring as used at the end of the set lever (shown in patent above referred 40 to) to be dispensed with, and there may be used in its place an unbending arm and roller, affixed to the end of the set lever, which forms a more exact and certain self 45 setting apparatus. Also in combining and arranging a friction roller, and slotted plate, with a setting scale, and hand or manual setting apparatus attached to and operating the set rod, in the manner and for the purpose 50 hereinafter more fully shown. Also, in combining with a clutch lever and the driven friction gear wheel, as arranged on the carriage shaft, for feeding the carriage up to the saw and gigging the same back, 55 an eccentric bearing or journal box, con-

structed and arranged substantially as shown in Fig. 3 for the purpose of more certainly and quickly throwing said friction gear wheel in or out of contact with the drivers of said friction wheel; also in combining with the saw mill frame an offsetting apparatus, combined and arranged in the manner substantially as hereinafter fully specified, for the purpose of throwing the saw and frame off or back from the log, 60 in order not to scratch the saw or mar the lumber, during the gigging back of the carriage.

To enable others skilled in the art of constructing sawing mills, to make and use my 70 invention or improvements, I will proceed to describe the construction and operation of the same, including a description as far as is necessary, of the ordinary sawing mills in use, in order to show clearly the connection of my improvements with the same.

A A is the carriage; B, B, the head and tail blocks, having the sliding racks C, C, sliding in grooves in the usual manner.

D is a set rod, provided with pinions at 80 each end, which gear into the sliding racks.

E is a self setting lever arranged on the set rod so as to have its outer end move freely up or down, the extent of downward movement being fixed by a rest (a). This 85 set lever is provided with grippers or dogs for operating on the set rod, in the usual known manner, but the outer end of said set lever, instead of having a knuckle joint as heretofore used, is provided with a fixed 90 arm, with friction roller (a') which, as the feed motion of carriage commences, traverses up the surface of the inclined plane F, and by means of the grippers or dogs of the set lever acting on the set rod, causes the 95 set rod to revolve partially, thereby operating the racks so as to give the required set to the log. Said inclined plane has its upper end made with a bearing or stud (c) (provided with a set screw (e)), which slides up 100 or down in slot (d) in the standard G, for the purpose of adjusting the height of said plane to the amount of set required for the log. Said standard having a graduated scale as seen in Fig. 2, to regulate the height 105 of inclined plane, for a certain amount of set of the log. This mode of attaching the inclined plane to the standard allows the lower end of said plane to rise as the arm and roller of the set lever passes under it on 110

the reverse or back motion of the carriage as shown by dotted lines in Fig. 2.

H is a hand setting lever, constructed, operating and attached to the set rod in the usual manner. To the outer end of this lever is affixed a link (f), connecting with the weighted lever I. Arranged upon the saw frame J J is the scale (g). Upon this scale is arranged a slotted plate (h), made adjustable by means of the set screw (i). At the end of this plate is affixed in a vertical position, the friction roller (j), against which the log rolls when set for sawing. This combination of the friction roller, slotted plate, scale, weighted lever, and set lever, is for the purpose of obtaining accurate and expeditious hand setting of the log—when such mode is wanted or preferred.

K is the driven friction gear wheel, keyed to the carriage shaft L, which has the pinion (k) meshing into the rack M, affixed to the carriage, for the purpose of giving feed motion to the log, and reversing or gigging back the same when a cut is made. This wheel K has an eccentric bearing or journal box N, as shown in Fig. 3 in which the journal (l) of carriage shaft L runs, so that when the clutch lever O is shifted either back or forth by hand or automatically; it so operates upon the eccentric journal box and journal (l), so as to bring either of the drivers P, or Q, in contact with the driven wheel K, thereby giving feed motion to the carriage and log, or reverse or gig back the same when desired.

The automatic feed or gig motion of the carriage, is produced in the usual manner by means of trips affixed to the carriage, and striking upon the usual arrangement of devices for effecting that purpose.

Upon the standards R, R, of the saw frame J, J, are arranged the offsetting plates S, S, having slots or yokes (m, m₁) at their outer ends, the lower ends of said standards

are so constructed as to slide in slots or grooves (n n) made in the bed plates T, T, of saw frame. Within the slots or yokes (m, m₁) are arranged and worked the eccentrics, (o, o), the eccentrics turning upon pins, (p p) firmly fixed in the bed plates T T. The eccentrics have levers (q, q₁) projecting outward from their under sides, by means of which they are operated. The ends of said levers are connected by connecting rod U, to the clutch lever O, so that the off set apparatus is operated either by hand or automatically,—for the purpose of throwing the saw off from the log, in order not to scratch the saw or mar the lumber, during the gigging back of the carriage. This off-setting apparatus, may be so connected to the clutch lever by means of the connecting rods, so as to offset only the saw end of the saw frame from the log for single cut mills, and for double cut mills, to offset alternately each end of the saw frame, or the connecting rods may be so connected to the clutch lever, as to give an even lateral offset to the whole saw frame when desired.

Having fully described my invention, what I claim as new and desire to secure by Letters Patent is:

1. The combination of the friction roller (j) and slotted plate (h); with the scale (g), hand lever I, set lever H, set rod D, and sliding racks C C, arranged and operating substantially in the manner and for the purposes as herein specified.

2. I also claim the combination of the eccentrics (o o) and offsetting plates S S; with the bed plates T T, connecting rod U, and clutch lever O constructed and operating for the purposes substantially as herein described.

KINGSLEY R. OLMSTED.
